PAUL HELMA AND KURT BAUCH, OF AKRON, OHIO, ASSIGNEES TO GOODYEAR-ZEPPELIN CORPORATION, OF AKRON, OHIO, A CORPORATION OF DELAWARE

WIRE NETTING FOR AIRSHIPS

Application filed March 7, 1929. Serial No. 345,035.

This invention relates to wire netting, and it has particular relation to wire netting adapted to support portions of the gas cells employed in rigid airships.

5 One object of the invention is to provide a netting which is so constructed that the gas cells of an airship will not be injured by impinging against them.

Another object of the invention is to provide a wire netting, the several elements of which are connected together in such manner as to prevent crossing of the wires, as well as to avoid injury of gas cells which engage it.

15 Heretofore, wire nettings employed for supporting the gas cells of airships have been composed of relatively stiff wires which were interwoven. In order to provide proper connection between the several

20 interwoven wires, the intersecting portions thereof were bound with suitable material and thereafter soldered. Such construction of nettings required much labor and also extensive working space. By binding or

25 soldering the intersecting portions of the wires, uneven joints resulted which were likely to injure the fabric, and there was also danger of the fabric being caught and torn at the corners of the meshes of the

30 netting. These disadvantages are obviated by providing a construction in which the binding and the crossing of the wires is obviated.

For a better understanding of the invention, reference may now be had to the accompanying drawings, forming a part of the specification, of which;

35 Figure 1 is an elevational view of a portion of a netting, the wires of which are connected together according to the invention;

40 Figure 2 is a cross-sectional view taken substantially along the line II—II of Figure 1;

45 Figure 3 is an edge elevational view of another form of connection for a wire netting;

50 Figure 4 is a cross-sectional view taken substantially along the line IV—IV of Figure 3; and

Figure 5 is a fragmentary elevational view, on a smaller scale, of a netting installed in the hull of an airship.

In practicing the invention, a netting 10 constituting a bulkhead is provided, which 55 includes identical wires 11 and 12. In Figure 5 one of the wires 12 is shown separately for the purpose of illustrating the manner in which it is bent alternately in opposite directions in the same plane to 60 provide a zig-zag shape. This shape may be effected before or after the wires are assembled in net form. The central portion of the netting is provided with a ring 13 for securing the inner ends of the wires 65 11 and 12, and the outer ends of the latter are connected by means of bridles 14 to a main ring 15 of an airship hull 16.

Adjacent bent portions of the wires 11 and 12 are connected by means of clamps 70 17 which firmly engage the wires and maintain their contiguous portions in a common plane. Each of the clamps 17 is composed of two sections 18 and 19, one of which is provided with a pair of curved grooves 75 20 and 22 for receiving the contiguous similarly curved portions of the wires 11 and 12, respectively. Also, the section 18 is provided with ribs 23 which fit within grooves 24 of greater depth than the thickness of the ribs, for the purpose of properly centering the two sections of the clamp in assembled relation. A securing bolt 25 having a head 26 counter-sunk within a recess 27 of the section 19 is screw-threaded into 80 the section 18. A polygonal opening 28 is provided in the head 26 for the purpose of receiving a suitable tool that can be employed to turn the bolt. It will be observed that the curved portions of the grooves 20 and 22 receive corresponding curved portions of the wires 11 and 12 circumferentially about opposite sides of the bolt 25, thereby providing a connection which positively prevents sliding of the wires with 85 respect to each other and with respect to the clamp.

Another form of clamping device 30, shown by Figures 3 and 4, comprises two sections 32 and 33 provided with grooves 100

34 that are curved as indicated at 35 for the purpose of receiving in the same plane curved contiguous portions 36 of the wires 11 and 12. The sections 32 and 33 of the 5 clamp are secured rigidly together by means of a rivet 37. Interfitting complementary portions 40 and 41 maintain the sections 32 and 33 in proper registering relation. The entire outer surfaces of both of the clamps 10 17 and 30 are rounded in order to obviate sharp corners. Also, it will be observed that the clamps are sufficiently large to cover the corners of the meshes of the netting, thereby avoiding the possibility of injury to material such as fabric which might be caught 15 therein.

From the foregoing description it will be apparent that the invention provides a relatively smoothly jointed netting which requires a relatively small space for the assembling thereof, and which can be assembled without involving complicated operations at the place where the netting is to be employed.

25 Although we have illustrated only the preferred forms which the invention may assume and have described those forms in detail, it will be apparent to those skilled in the art that the invention is not so limited, 30 but that various modifications may be made therein without departing from the spirit of the invention or from the scope of the appended claims.

What we claim is:

35 1. A bulkhead adapted to be installed in an airship main ring, comprising wires of zig-zag configuration connected to the main ring, adjacent zig-zag wire portions being connected together in uncrossed relation to 40 present a relatively smooth contact surface upon which gas cells are adapted to bulge.

2. A bulkhead adapted to be installed in an airship main ring comprising wires of zig-zag configuration connected to the main 45 ring, clamps connecting together contiguous zig-zag portions of the wires, said clamps presenting a smooth and rounded configuration to prevent injury to gas cells adapted to contact therewith.

50 3. A bulkhead adapted to be installed in an airship main ring comprising a central connection, a plurality of wires radiating from the central connection, each wire being zig-zag in configuration, adjacent wires being connected together at spaced intervals in uncrossed relation, and means for connecting the outer ends of the wires to the main ring.

55 4. A bulkhead adapted to be installed in an airship main ring, comprising a central connection, a plurality of wires radiating from the central connection, each wire being zig-zag in configuration, clamps connecting the wires in uncrossed relation at the bight 60 portions of zig-zag configurations, said

clamps presenting smooth surfaces for preventing injury to airship gas cells and means for connecting the outer ends of the wires to the main ring.

In witness whereof, we have hereunto 70 signed our names.

PAUL HELMA.
KURT BAUCH.
